UNITED STATES PATENT OFFICE

2,445,466

FLUID FUEL COMBUSTION DEVICE

Albert A. Arnhym, Los Angeles, Calif., assignor
to Solar Aircraft Company, San Diego, Calif.,
a corporation of California

Application June 2, 1944, Serial No. 538,517

3 Claims. (Cl. 263—19)

1

This invention relates to combustion devices burning fluid fuels, such as gasoline, and is particularly useful for providing heated air on gasoline powered vehicles such as aircraft.

An object of the invention is to provide a fluid fuel combustion device that has a large heat capacity in proportion to its weight and bulk.

Another object is to provide a device for burning liquid fuel such as gasoline substantially completely so that the exhaust contains no unburned and poisonous ingredients such as carbon monoxide.

Another object is to provide a combustion device that has substantially uniform heat capacity, and operates reliably over a wide range of air pressures corresponding to different altitudes.

Another object is to provide a gasoline burning combustion device that is capable of burning aviation gasoline containing lead without the lead interfering with the operation of the heater or being discharged as a toxic ingredient with the exhaust gas.

Still another object is to provide a gasoline burning device suitable for operation on aircraft, in which the controls are largely automatic so that it is only necessary to vary the rate of flow of fuel to the heater to vary the output, the control of the air supply being automatically effected to compensate for variations in the fuel supply and for variations in the atmospheric pressure due to altitude changes.

Various other more specific objects and features of the invention will become apparent from the detailed description to follow with reference to the drawings.

Essentially, the heater of the present invention comprises an elongated combustion chamber, into which a rich mixture of fuel and air is forced at one end and auxiliary air to complete the combustion is introduced at successive points between the ends of the combustion chamber so as to completely burn a hydrocarbon fuel to water and carbon dioxide. In addition, the entire supply of the combustion air is automatically controlled with reference to the rate of flow of the fuel so that despite variations in the rate of fuel flow or in atmospheric pressure, the proper amount of air for complete combustion is provided. The hot products of combustion issuing from the combustion chamber are mixed with additional cold air to provide a large volume of air heated to a temperature desirable for introduction either into passenger compartments or to any portion of the airplane structure where heat is desired.

2

In the drawings:

Fig. 1 is a side view with portions broken away of an actual embodiment of the heater;

Fig. 2 is an end view looking at the right end of Fig. 1, with portions broken away;

Fig. 3 is a schematic view showing, in addition to the structure of Figs. 1 and 2, certain auxiliary elements necessary in the complete system; and

Fig. 4 is a detail section of a portion of the perforated tube through which the fuel-air mixture is discharged into the combustion chamber.

The elements of the heater and their functions will first be described with reference to Figs. 1 and 2, after which the operation will be described with reference to those figures in conjunction with the schematic diagram of Fig. 3.

The heater is largely self-contained within a housing which comprises a cylindrical casing 10 and an auxiliary casing 11, the latter consisting of a pair of end walls 12 and 13, side walls 14 and 15 and a top wall 16. The end walls 12 and 13 have concave lower edges fitting against and secured to the cylindrical casing 10, a portion of which forms the bottom wall of the auxiliary casing. The side and top walls are secured to the end walls and are removable.

The cylindrical casing 10 contains a combustion chamber 17 therewithin, the combustion chamber being centrally disposed within the cylindrical casing and extending through almost the full length of the latter which serves as a conduit to conduct the air to be heated past the combustion chamber.

As shown, the heater is particularly adapted for burning gasoline which is supplied from a reservoir (not shown) through tubing 18 to an electrically driven fuel pump 20, the pump 20 delivering the fuel at a rate of flow proportional to the pump speed so that the rate of flow can be varied by varying the current supplied to the pump in a manner to be described later. From the pump 20 the fuel flows through an electrically actuated safety shut-off valve 19 and through a feed line 22, from the end of which it is sprayed into an air stream flowing into the combustion chamber 17.

Air is supplied from any suitable source, such as a blower 12, through a duct 23 and through a control valve 24 to a manifold 25, from which it flows to the combustion chamber through three different paths. Thus a portion of the air flows from the left end of manifold 25 through a duct 26, which duct contains the end portion of the fuel line 22 so that all of the air flowing through duct 26 is mixed with the fuel issuing from the

line 22 to form a rich mixture which is conducted into a perforated tube 28 which extends into the left end of the combustion chamber and is provided with a large number of apertures 29, through which the mixture is discharged in numerous small jets into the combustion chamber. The mixture burns as it issues from the apertures 29 but since, as previously stated the mixture is over rich, the combustion is not completed at this point. To complete the combustion, auxiliary air enters the combustion chamber from the manifold 25 through a second duct 30 and through a third duct 31. The duct 30 is juxtaposed to the inlet tube 28 and discharges directly into the combustion chamber through a single large orifice. On the other hand, the duct 31 communicates with the combustion chamber substantially at its middle and the air is distributed through an annular row of apertures 32 in a venturi member 33 which is provided in the combustion chamber. The outer surface of the venturi member 33 defines, with an annular collar 34, an annular manifold through which the air is distributed from the duct 31 to the apertures 32.

The air is supplied to the manifold 25 by the control valve 24 at a relatively low pressure, only slightly above the pressure of the surrounding atmosphere, and the venturi member 33 reduces the pressure within the combustion chamber adjacent the apertures 32 so as to facilitate the entry of a sufficient amount of air through the holes 32 to complete combustion of the fuel. This combustion is substantially completed by the time the gases reach the right end of the combustion chamber where they are discharged laterally into an air stream which flows through the cylindrical casing 10 from right to left.

The first or leftmost portion of the combustion chamber 17 acts in part as a generator in which primary combustion takes place, which combustion is facilitated by the supply of secondary air received through the duct 30. By the time the gases leave the part of the combustion chamber adjacent the inlet tube 28, they are still burning but contain a considerable percentage of carbon monoxide. The mixture in the combustion chamber to the right of the venturi 33 consists of burned exhaust gases, carbon monoxide and air, and the air is supplied in sufficient amount to complete combustion of the carbon monoxide so that the final exhaust products contain neither carbon monoxide nor any other unburned toxic gas or fumes.

As illustrated in Fig. 1, the cylindrical casing 10 of the heater is open at both ends and flow of air (hereinafter referred to as ventilating air) therethrough from right to left is merely indicated by arrows. In practice, however, it is to be understood that the casing 10 will be connected at its right end to a suitable source of air such as a scoop or a blower. If the heater is to be used only during flight, an air scoop suitably situated on the airplane will suffice but if the heater is to be used on the ground as well as in the air it may be desirable to provide a power driven blower. Irrespective of the nature of the source of the ventilating air supply, it will be connected to the right end of the casing 10 by a suitable duct.

There is preferably mounted between the combustion chamber 17 and the casing 10 a cylindrical baffle 36 which reduces the radiation of heat from the combustion chamber to the casing 10 and increases the transfer of heat to the venti-

lating air. As shown in Fig. 2, this cylindrical baffle 36 has vertically extending flanges at the top and bottom which connect it to the casing 10. The combustion chamber itself is supported from the baffle 36 by numerous curved strips 37 which extend therebetween. By virtue of the curvature of these strips 37, they can readily yield to compensate for expansion and contraction of the combustion chamber as its temperature changes.

It will be observed from Fig. 1 that closely adjacent the outlet the combustion chamber is constricted to form a neck 38 of reduced diameter. This tends to increase the velocity of the ventilating air as it flows past the annular discharge orifice 39, which decreases the static pressure at that point and facilitates the flow of the products of combustion into the ventilating air stream. The annular discharge orifice 39 is formed in part by the rear end of the combustion chamber proper and in part by a cap 40 of cup shape having its concave side directed toward the end of the combustion chamber. This cap 40 serves not only as a deflector for deflecting the products of combustion laterally through the orifice 39 but also serves to accumulate a portion of the lead deposit that results from operation with high octane aviation fuel containing tetraethyl lead.

In addition to the functions recited, the cylindrical shroud 36 also aids in sound-proofing the assembly and the shroud is sufficiently cooled by the air stream flowing between it and the cylindrical casing 10 to cause further deposition of lead in it. A filter 42 at the extreme left end of the casing 10 abstracts what lead may be left in the air prior to its discharge from the heater.

It is to be noted particularly that the ventilating air flows through the heater in direction opposite to the flow of the burning gases within the combustion chamber. This construction has distinct advantages. It prevents leakage of any burning gases into a duct used to convey the heated air away from the heater since any gases that might be still burning at the time they issued from the annular orifice 39 are blown back along the outer surface of the combustion chamber and quickly extinguished. Another advantage is that the ventilating air is applied while it is still relatively cold to the discharge end of the combustion chamber which gets considerably hotter than the inlet end, thereby preventing over-heating of the combustion chamber wall. The arrangement also causes thorough mixing of the products of combustion issuing from the orifice 39 with the ventilating air within the shroud 36.

Heretofore when burning leaded gasoline in a heater having a perforated member such as the tube 28 through which a mixture of fuel and air is discharged and ignited, trouble has been encountered due to depositions of lead compounds adjacent the outer orifices of the apertures in the member which eventually clog the apertures and render the device inoperative. Such difficulties are prevented in the present construction by chamfering or counter-sinking the outer orifices of the apertures 29 as shown in the detail view of Fig. 4. It is found that with this construction as soon as a slight deposit has formed in the outer portion of an aperture it breaks away and the apertures remain clean for a long period of service.

As has been previously indicated, the rate of combustion and the quantity of heat generated is varied by varying the rate at which liquid fuel is delivered through the tubing 22 and the air

supply is automatically varied to correspond. This automatic control of the air supply is obtained with the valve 24 which is jointly responsive to the pressure of the fuel in the feed line 22 and to the air in the manifold 25. This valve comprises a casing 43 defining a straight-through air passage between the air supply duct 23 and the manifold 25, which passage is adapted to be variably blocked by a butterfly 44 which is connected by a link 45 to a diaphragm 46 mounted in a case 47. The under side of the diaphragm is exposed to the pressure in the manifold 25 on the discharge side of the butterfly 44 through an aperture 48, the link 45 extending through this aperture and through a slot 49 in the butterfly 44. A small amount of leakage takes place through the slot 49 but it is not important. The major portion of the upper surface of the diaphragm 46 forms one wall of a sealed chamber 50, the other walls of which chamber are constituted by the upper portion 51 of the diaphragm housing and by a Sylphon bellows 52 which extends vertically between the diaphragm and a fitting 53 in the cover 51, which fitting connects to the feed line 22.

By virtue of the construction described, the major portion of the upper area of the diaphragm 46 is exposed to the substantially constant pressure of the sealed chamber 50 and the remainder of the area is exposed to the pressure of the liquid in the fuel line 22. A light spring 55 moves the diaphragm 46 upwardly and closes the butterfly 44 when the fuel pump 20 is not operating and there is no pressure in the fuel line 22. However, when the device is set in operation and fuel pressure is developed in the feed line 22, this pressure acting on the upper portion of the diaphragm 46 that is within the Sylphon bellows 52, moves the diaphragm 46 downwardly, thereby opening the butterfly 44 and admitting air for combustion into the manifold 25. The air pressure within the manifold is applied through the opening 48 to the under side of the diaphragm 46 opposing the force exerted on the upper side of the diaphragm by the fuel pressure, and the butterfly 44 assumes a position in which the opposing forces are in equilibrium.

The structure described functions to provide the proper mixture of fuel and air for good combustion despite variations in the fuel supply resulting from variations in the speed (manually controlled) of the fuel pump 20 and variations in the absolute pressure of the air due to changes in altitude. The design is such that when the fuel pressure is at the maximum for maximum heat output and the altitude is such as to reduce the atmospheric pressure to the minimum value for which the heater is designed, the butterfly 44 is substantially wide open. At any lower altitude or at any lesser fuel pressure the butterfly is only partially open. At sea level with maximum fuel flow, the butterfly is about one-third open in a heater designed for use at a maximum altitude of 40,000 feet.

The air supply through the inlet duct 23 may come from a scoop on the surface of the airplane or from a blower. If desired, the same scoop or blower may be used for supplying both the combustion air and the ventilating air.

If for any reason the pressure of the air supplied through the duct 23 should be insufficient to balance the fuel pressure or, in other words, there is not enough mass flow of air for a given fuel flow, the butterfly 44 will tend to move beyond the wide open position, which would de-

crease rather than increase the flow of air. To avoid such a contingency, a limit control is provided which decreases the speed of the fuel pump 20 until its pressure balances the maximum available air pressure. This control includes a rheostat 56 which is varied in response to opening of the butterfly 44. Thus there is secured to one end of the shaft 57 of the butterfly the movable contact 58 of the rheostat 56, which movable contact, through the initial portion of the opening movement of the butterfly 44, rides on a low resistance conductor 59 but during the final opening movement of the butterfly rides over the register 60. As will be explained in detail later with reference to the schematic diagram of Fig. 3, the rheostat 56 is connected in series with the motor of the fuel pump 20 so that it does not affect the speed of the pump so long as the movable contact 58 is on the low resistance conductor 59 but substantially reduces the speed of the fuel pump in response to final movement of the butterfly 44 into fully open position.

Should the air pressure drop below the value necessary to fully open the butterfly 44, a pressure responsive switch 61 (Fig. 2) connected to the valve casing 43 ahead of the butterfly 44 operates to open the circuit to the fuel pump and thereby shut the heater down. The circuit will be described in detail later with reference to the schematic diagram of Fig. 3.

In the event the air pressure within the valve casing 43 ahead of the butterfly should rise too high, it might interfere with the proper functioning of the butterfly 44 due to the creation of turbulence in the flow therewith and it is therefore desirable to provide a static relief valve 62 between the valve casing 43 and the cylindrical casing 10 so that in case of excess pressure some air can be vented from the casing 43 into the venting air passage of the heater. As shown, this relief valve 62 consists of a butterfly, the shaft of which is eccentrically disposed so that air pressure on the upper side thereof tends to open it. Opening movement is resisted by a torsion spring 63 surrounding one end of the butterfly shaft and connected between the shaft and the housing.

In addition to the electrical elements already mentioned, various other controls, both electrical and non-electrical, are incorporated into the system and they will now be described with reference to the schematic diagram of Fig. 3, in which parts corresponding to those of Figs. 1 and 2 bear the same reference numerals.

The system is usually operated from a source of direct current such as a battery 64, one terminal of which is grounded and the other terminal of which is connected to a supply lead 65 which extends to a combination rheostat and switch in a control unit 66 which may be remotely positioned from the heater proper if that is desirable. It will be observed that the lead 65 is connected through a fuse 67 to a movable arm or contact 68 which is adapted to ride over a low resistance contact 69 and also a resistor 70. The rheostat is shown in the off position. When it is desired to start the heater, the arm 68 is moved clockwise to make contact with the elements 69 and 70. Current thereupon flows through the contact 69 and through a lead 71 to an electrically driven blower 72, it being assumed that in this instance such a blower is provided for supplying the combustion air to the heater. As soon as the blower 72 attains its normal operating speed, it produces a static pressure within the valve casing 43 (Fig. 1) which actuates the pressure responsive switch

61 to close the contacts thereof and complete a circuit from the lead 11 over a lead 13 and thence through the winding of a relay 14, through a lead 15, through the winding of a thermal relay 16 and a lead 17 to an ignition wire 18, the other terminal of which is grounded. This ignition wire 18 is mounted on the exterior of tube 28 (Fig. 1) and is normally heated to a temperature sufficient to ignite fuel in the combustion chamber whenever the heater is in operation. To protect the ignition wire 18 from air currents that would tend to cool it excessively, a trough-like shield 19 is provided which is positioned substantially concentrically with respect to the wire 18 and between it and the tube 28.

The relay 14 operates almost immediately upon closure of the circuit described and the thermal relay 16 operates shortly thereafter. Operation of relay 14 closes a first pair of contacts 141, completing a circuit from lead 13 through the solenoid relay 19, opening the latter to permit fuel to flow from the fuel pump 20 to the feed line 22.

Movement of the movable contact 68 onto the left end of the resistor 70 applies current directly over a lead 80 and to one contact of a pressure responsive switch 82 on the cylinder 10. If there is a sufficient supply of ventilating air, the pressure responsive switch 82 will be closed, completing a circuit to the low resistance side 83 of the rheostat 56 associated with the butterfly valve 44 and thence over the movable contact 58 and a lead 83 to a second pair of contacts 742 on the relay 14. Assuming that this relay has been previously operated as described, current is supplied over the lead 83 and the contacts 742 and the contacts 761 of the thermal relay 16 to the fuel pump 20, causing the latter to operate at maximum speed. The purpose of the thermal relay 16 is to insure that the ignitor wire 18 has time to heat before the fuel pump 20 starts delivering fuel to the combustion chamber.

Operation of the fuel pump 20 develops pressure in the feed line 22, which pressure acts on the diaphragm 46, as previously described, to open the butterfly 44 and admit the proper amount of air for combustion to the manifold 25, and the resultant mixture of fuel and air issuing from the apertures 29 into the combustion chamber is ignited by the ignition wire 18.

The heat output may be reduced manually by rotating the movable contact 68 in the control unit 65 to gradually introduce the resistor 70 into the circuit and thereby slow the fuel pump 20. Furthermore, if for any reason the blower 72 fails to supply sufficient air for proper combustion for the amount of fuel delivered, the butterfly 44 is moved toward fully open position to introduce the resistor 56 into the circuit, thereby slowing down the fuel pump 20.

Should the supply of ventilating air fail at any time, pressure responsive switch 82 functions to shut down the fuel pump and if the supply of combustion air becomes insufficient to support proper combustion even with the butterfly 44 fully open, then the pressure responsive switch 61 opens its contacts to de-energize the relays 14 and 16, which function to not only de-energize the fuel pump 20 but also to release the solenoid valve 19 and positively stop further supply of fuel.

By virtue of the fact that the ignition wire 18 is connected in series with the thermal relay 16 and the relay 14, failure (burning out) of the ignition wire immediately results in shut down of the system.

To indicate to the operator whether or not the system is functioning, various signal lamps may be mounted on the control unit 65. Thus a lamp 84 is connected between the lead 66 and a lead 85 extending to a thermal switch 86 mounted within the casing 10 to indicate whether or not heat is being supplied. A second lamp 87 is connected directly to the contact 69 to indicate whether or not current is being supplied from the battery 10 64 when the switch has been turned on.

When the system described is in use on an airplane flying at varying altitudes, the density of the air supplied for combustion is substantially less at high altitudes than at low altitudes. In other words, the device forcing the combustion air into the heater, whether it be the blower 72 of Fig. 3 or a scoop on the exterior of the airplane, is not intended to develop a pressure equal to the actual variation in pressure between sea level and the higher altitude at which the plane may fly. The heater is designed to provide a predetermined amount of heat when supplied with relatively thin air at high altitude and then to reduce the volume of air supplied (for the same fuel supply) when flying at lower altitudes. This method is distinct from that of designing the heater for normal operation at sea level and then supercharging it to compensate for decreased air densities at higher altitudes. A particular advantage of the system is that it requires only a single control, the rheostat in the control unit 65, all other controls being fully automatic.

An actual heater designed to produce a maximum heat output of 250,000 B. t. u. per hour at an elevation of 40,000 feet may be dimensioned and equipped as follows:

Overall length of the combustion chamber	17	18 $\frac{3}{4}$ "
Diameter of the combustion chamber in the cylindrical portion at the left end	30	2 $\frac{3}{8}$ "
Diameter at the throat of the venturi 33	35	1 $\frac{1}{2}$ "
Length of the venturi 33	30	2"
Maximum diameter of the combustion chamber between venturi 33 and the neck 38	45	3"
Diameter at the neck 38	50	1 $\frac{3}{4}$ "
Diameter of the discharge end of the combustion chamber	55	2 $\frac{1}{2}$ "
Width of the annular discharge orifice 39	60	1"
Diameter of the shroud 36	65	5 $\frac{1}{2}$ "
Diameter of the casing 10	70	7"
Diameter of air duct 31	75	3/4"
Diameter of air duct 30	80	3/4"
Diameter of air duct 26	85	1 $\frac{1}{8}$ "
Approximate lengths of air ducts 30 and 31	90	3 $\frac{3}{8}$ "
Diameter of jet in end of feed line 22	95	drill #75
Diameter of burner tube 28	100	1"
Number of the holes 29	105	146
Diameter of the holes 29	110	drill #40
Diameter of the diaphragm 46	115	6"
Effective diameter of the Sylphon bellows 52	120	3/4"
Maximum capacity of the fuel pump 20	125	gal/hour 4
Differential pressure (above atmospheric) required in duct 23 for full capacity operation	130	water 8"

Although for the purpose of explaining the invention a specific embodiment thereof has been described in great detail, many changes from the specific construction shown will be obvious to those skilled in the art. For example, although as described the device is primarily intended for heating space on an airplane or other location,

it may also be employed in jet propulsion or as the combusting part of a gas turbine in which heat is incidental and the primary object is to produce a large volume of gas at high velocity.

It is also to be noted that although gasoline has been particularly mentioned as a fuel, other liquid fuels, such as kerosene or alcohol may be employed. Furthermore, gaseous fuels, such as propane, butane or natural gases may be used by substituting a pressure reducing valve for the fuel pump 20 and substituting a throttle valve for the control rheostat 70.

It is also to be particularly noted that although as shown in the drawing the gases passing from the left end of the passage between the combustion chamber and the baffle 36 are mixed with the gas (air) passing between the baffle 36 and the outer case 10, it is not essential that they be so mixed for delivery together. The gas from within the baffle 36 may, if desired, be transmitted separately and used for anti-icing and similar purposes only while using only, the relatively pure hot air from the annular passage formed by the shroud or baffle 36 and the outer casing 10 for the heating of passenger compartments.

I claim:

1. In a combustion device: an elongated combustion chamber, means for introducing a mixture of air and fuel into said combustion chamber at one end thereof, the other end of said chamber being open for the discharge of products of combustion, a casing surrounding said combustion chamber and adapted to have a stream of air to be heated forced therethrough in direction opposite to the flow through said combustion chamber, a cap juxtaposed to the open end of said combustion chamber for deflecting products of combustion laterally into said air stream, said casing being fully open at the ends whereby the smallest cross-sectional area of said air stream occurs in the annular space between said casing and said combustion chamber.

2. Apparatus as described in claim 1 in which the combustion chamber tapers from a larger cross-sectional dimension at said open end to a smaller cross-sectional dimension at a point spaced longitudinally from said open end, whereby the cross-sectional area of said air stream is reduced at the area of ingress into said stream of the products of combustion, to reduce the pressure of the stream and promote the ingestion into the stream of said products of combustion.

3. Apparatus as described in claim 1 in which that portion of said casing that is juxtaposed to said combustion chamber is substantially of uniform cross-sectional area, and said combustion chamber tapers from a maximum cross-sectional area in the general region of its mid-portion to a minimum cross-sectional area a short distance from its open end, and then tapers to a cross-sectional area intermediate said maximum and minimum areas at said open end.

ALBERT A. ARNHYM.
